CLAIM

I claim the ornamental design for a window cleaning tool, as shown and described.

DESCRIPTION

FIG. 1 is a perspective view of a window cleaning tool embodying my invention;

FIG. 2 is a left-hand end view thereof;

FIG. 3 is a front view thereof;

FIG. 4 is a bottom view thereof; and,

FIG. 5 is a top view thereof.

The broken lines in FIG. 5 illustrate environment and form no part of the claimed design.

1 Claim, 3 Drawing Sheets
